REMOTE CONTROL SYSTEM

Eugene L. Triman, Chicago, Ill.

Original application February 15, 1947, Serial No. 728,765, now Patent No. 2,557,581, dated June 19, 1951. Divided and this application October 14, 1950, Serial No. 190,081

11 Claims. (Cl. 340—206)

This invention pertains to signalling and signal controlled apparatus of general application, but particularly useful in conjunction with remote control systems and the like; this application being a division of my copending application Serial No. 728,765, filed February 15, 1947, now Patent No. 2,557,581 dated June 19, 1951.

In its broader aspects, the invention has as one of its principal objects the provision of means for transmitting a signal having a certain predetermined characteristic and utilizing the transmitted signal to control a signal-matching means, at a receiving station, which will effect a matching or duplication of the characteristic of the transmitted signal to provide a resultant control voltage or factor useful in the control of some desired instrumentality or apparatus.

More particularly, it is an object of the invention to provide a remote control system utilizing a transmitted signal, for example a radio frequency carrier emitted or modulated as to pulse duration, together with a signal-matching means operating under control of the transmitted signal to provide a matching signal reproducing exactly the selecting characteristic of the transmitted signal, the identity or lack of identity of the matched and matching signals being utilized for control purposes at a receiving station remote from the source of transmitted signals.

A more detailed object of the invention is the provision of a remote control system of general application, and especially useful in one of its adaptations for the control of automatic phonographs and the like by signals transmitted over a metallic circuit, including commercial power lines, or by space wave propagation, the transmitted signal having a control or selecting characteristic and actuating a local signal generator at the receiving station which is varied in a certain manner under control of the transmitted signal until the locally generated signal is identical in control characteristic to the transmitted signal, the identity or lack of identity between the transmitted and locally generated signals being factors in the actuation of the controlled device, in this instance, the automatic phonograph, to effect for example the selection of a certain phonographic record and the playing thereof.

A further objective aspect of the invention is the provision of remote control apparatus of the class described for automatic phonographs and the like, which utilizes selecting signals transmitted by carrier over a metallic circuit or otherwise, and in which selection is effected as a result of matching or duplication by a local signal generator of the transmitted signal to afford a resultant control voltage or factor.

Another particularized object is the provision of selecting means actuated responsive to the matching of a local signal with a transmitted selecting signal, both said signals being a phasal function of a standard alternating or pulsating reference voltage such as commonly supplied over commercial power lines.

In addition to the foregoing are other objects and as-

2

pects of novelty and utility of detailed and complex character and pertaining to functional and circuit arrangements which are described and explained in view of the annexed drawings, in which:

5 Fig. 1 is a block diagram of the remote control system in its broader aspects;

Fig. 2 is a block diagram of an embodiment of the system utilizing variable pulse duration as the signal characteristic;

10 Fig. 2-A is a circuit diagram for a selector-transmitter for the variable pulse system of Fig. 2;

Fig. 2-B is a circuit diagram for a receiving selector unit cooperable with the transmitter of Fig. 2-A.

Broadly, the functional aspects of the novel remote control system are depicted in Fig. 1, wherein a characteristic control signal is emitted from the block source 15 and transmitted by any medium to the remote point.

The characteristic of the control signal in the present embodiment is that of pulse duration, derived from what 20 is termed herein as "phased modulation"; and, in general, it is contemplated that the preferred transmission medium may be a metallic circuit, such as the commercial power lines, for reasons heretofore and hereinafter alluded to, it being understood, nevertheless, that other media are practicable and contemplated, especially space 25 wave propagation at radio frequencies.

As indicated by block 16, Fig. 1, the received signal is utilized to control the operation of a source of matching signal energy, designated as the matching signal generator of block 17, through the medium of a control circuit means 18.

The incoming signal being characteristically modulated as to pulse duration, it is the function of generating means 17 to produce signals the duration of which is progressively varied above and below some limiting value, and these local signals are fed into a comparor 19, along with the actual incoming signals by-passed along path 20.

The local generating means 17 will continue to produce signals of different pulse length until the generated signal is identical in duration to the incoming control signal, at which time there is in effect a zero resultant control voltage, preferably, which may be utilized in various ways to actuate the controlled device of block 22.

45 The aforesaid control voltage, as represented in block 21, is some function of the incoming and locally generated signal voltages as these are mutually effective in the comparor, it being apparent that the resultant control voltage may be zero or different from zero, for control purposes.

50 In Fig. 2 there are depicted diagrammatically the components of a remote control system utilizing pulse duration as the control characteristic. A forward pulse generator 25 produces pulses having a predetermined duration, as selectively varied for example by the "master control" means there-indicated, and pulses of this duration are propagated or directed to the remote control point or receiving station by transmitter means 26. In conjunction with the forward pulse generator, the master control is depicted schematically as a phase-shifting network, it being contemplated, as will more particularly appear hereinafter, that the limiting values of the pulse duration may conveniently be set between the beginning and end of a single cycle of commercial power line voltage, at 60 cycles for example, and the duration of such

65 pulse may be controlled selectively by applying an effective voltage at an instant during said cycle, determined by said phase-shifting network, to the control grid of a thermionic pulse generator or an oscillator.

70 The transmitted pulse from the control station is suitably amplified by means 27 at the remote point, and rectified in signal detecting unit 28 to provide a posi-

tive incoming pulse for both control and comparison purposes; and this pulse is fed to a differentiating circuit means 29 and also to a comparor circuit means 30.

The differentiating means, as will appear more particularly in the circuit description, functions to produce a short triggering pulse for control of the local matching signal generator 32, which pulse is amplified in unit 31.

The local generating means 32 is preferably a single-cycle multivibrator adapted to produce in rapid succession, short pulses the duration of which may be varied by varying a circuit component, such as the capacity 33, to produce what is preferably referred to as the reverse pulse, which is fed into the comparor circuit means 30, along with the positive incoming pulse component from the detector stage 28.

If the incoming forward pulse and the locally generated reverse pulse are of substantially identical time duration, a thermionic control circuit or rectifier 34, actuated by the resultant control voltages from the comparor 30, will cause a master control motor 35 to stop. This motor is coupled to the reverse pulse generator control or capacity 33 to vary the latter so long as the motor runs in one or the other direction, which it will continue to do so long as the forward and reverse pulses are not identical. It will be apparent that the control motor 35 must always rotate predetermined amounts between opposite, fixed limits corresponding to positions of the capacity control 33 to effect matching of local with incoming signals, by reason of which this motor may also be utilized to control a desired device, such as a phonograph selector switch or the like.

In Fig. 2-A is shown a wiring diagram for a selective control unit for transmitting pulses of selectively varied duration in conjunction with a phonograph control system, the transmission medium in this instance being the commercial power lines 40 supplying 60 cycle current to the primary 41 of a power transformer, one secondary winding 42 of which supplies plate potential via lead 43 and R. F. choke 44 to the plate 45 of a thermionic oscillator tube, the plate circuit being completed to the cathode 46 mainly via leads 47, coin switch 48, closed momentarily by deposit of a coin in the usual coin control (not shown) provided for phonograph selectors, and conductor 49 back to said high-potential secondary winding 42 through the winding 50 of a locking relay and conductor 51.

The momentary flow of plate current in the aforesaid plate circuit will cause the locking relay to pull up and close its own interlock circuit via contacts 52, normally closed contacts 53-54 and cathode lead 47, a timing capacity 55 being shunted across relay winding 50 through relay contacts 56, so that the relay continues to hold up although plate current is flowing only during half-wave intervals of the 60 cycle supply voltage.

The grid circuit of the oscillator tube, from grid 58 connects through grid condenser and leak 59 to one terminal 60 of a tank inductance, the opposite terminal 61 of which is coupled through capacity 62 to plate 45, and via conductor 63 and line coupling capacity 64 to one side of the power lines 40. This grid circuit is completed to cathode from tap 66 on the tank coil via conductor 67 and radio frequency capacitor 68 to cathode 46, the tank coil being tuned to the desired R. F. line transmission frequency by shunt capacitor 69.

Normally, contacts 70, ganged with contact 54, are closed to complete a short circuit around grid inductance 60-66 via conductors 67A and 71, as a result of which the oscillation of the aforesaid circuit is prevented until such time as one of the selector push buttons 72A, 72B . . . 72G is depressed for purposes of effecting a phonographic selection.

When the locking relay has its coil 50 energized as aforesaid, following deposit of a coin, a mechanical interlock (indicated schematically by the dash-dot line, switches 54, 70) is set up by which any of the push

buttons 72A . . . 72G depressed will be locked in set or closed condition; and as one result of the selective depression and locking-in of, say, the push button 72B, switch contact 54 will be transferred from contact 53 to contact 53A, and also, contacts 70 will be opened, lifting the short-circuit around grid inductance 60-66, so that the oscillator circuit may now oscillate during appropriate half-wave intervals of the supply frequency.

As another important incident of setting of selector push button 72B as aforesaid, contacts 73B thereof close, thereby connecting the tank coil cathode lead 67 through a phase-shifting resistor 74B, conductor 75 to one terminal of a phase-shift grid-bias secondary winding 76 of the aforesaid power transformer, the remaining terminal of which winding connects via conductor 77 and series phase-shift capacity 78, conductor 79, and phase-shift resistors 74H, 74G . . . 74C to the depressed push button contacts 73B, by reason of which a grid-biasing voltage is applied to conductor 67A from winding 76, the phase of which is shifted (in a predetermined amount dependent upon the values of phase-shifting components 78 and the connection to the resistor network 74B . . . 74H) relative to the plate voltage.

As a result of applying a selectively phased grid bias to the oscillator during intervals of relatively phased oscillation as aforesaid, radio frequency impulses of selected duration are impressed upon the power lines 40 through coupling means or capacities 64, 65, to be picked up by remotely situated receiving and selecting apparatus 30 now to be described.

A plurality of selecting pulses of predetermined duration will be impressed upon the transmission medium or power lines following depression of one of the selection push buttons as aforesaid, these pulses following in very rapid succession for a determined length of time considered adequate to assure response at the remote controlled station, said length of time being dependent upon the time required for the timing capacity 55 to discharge, it being recalled that as an incident to depression of a push button, contact 54 transferred to contact 53A, thereby shunting the cathode return 47 around relay winding 50 via contacts 53B and lead 53C to conductor 51. As soon as the relay falls back, both the electrical and mechanical interlocks set up thereby are broken, with the result that contacts 70, controlling oscillation, and contact 54, are restored to normal condition, awaiting the next coin-operation of the control unit, and the particular push button which had been depressed and locked down, is freed and normalized.

In Figure 2-B is shown a circuit diagram of a pulse-duration selecting means, wherein the pulse generating and transmitting means indicated diagrammatically in blocks 80 and 81 apply a selecting pulse at radio frequency, for example, to power lines 40, from which the pulse signals are picked up by suitable coupling means, e. g. the line coupling capacities indicated, and passed through a suitable amplifying means 82, preferably, before rectification by the usual signal detecting means 83.

The rectified incoming selecting pulses are fed to a differentiating means through coupling transformer 84, said means consisting in this instance of capacity 85 and resistance 86 calculated to give a time constant resulting in a very short pulse for triggering the local pulse generating means, this triggering pulse being coupled via conductors 87 to the grid-cathode circuit, including bias potential means 88, of biased amplifier means 89.

The differential triggering pulse, after amplification by the biased amplifying means 89, is applied via conductor 90 to the grid 91, of one of a pair of triodes in the local signal generator, through coupling capacity 92, cathode 93 for this triode being returned to the common ground 94.

The local signal-matching generating means is depicted as a form of single cycle multivibrator in which pulse

changes in the circuit 95 of first triode plate 96 are coupled through a variable capacity 97 to the control grid 98 of a second triode, which is coupled through parallel capacity 99 and resistance 100 to the generator output lead 101, along with the grid 91 of the first triode. Capacity 97 controls the duration of each pulse generated by this signal-matching means, responsive to triggering impulses from the differentiator, and said capacity is arranged to be progressively, and in a sense retrogressively, varied by means such as the motor 105, which, as will appear, is connected to run in opposite directions so long as the incoming and locally generated signals do not match in duration.

Means for comparing the locally generated matching signal and the incoming control signal includes a comparor consisting of a first gas triode or Thyratron V₁, the control grid 106 of which is coupled through capacity 107, conductor 108, to the line side of differentiator capacity 85, so that the same signal utilized for triggering is impressed upon the grid of the first gas triode to fire the latter, while the local matching signal is applied from generator output lead 101 through capacity 109 to the control grid 110 of a second gas triode V₂ in the comparor to fire the same. The plates of both triodes V₁ and V₂ are supplied from a quenching supply voltage source 111 of suitably high frequency, for example about 420 cycles, adequate to provide rapid restoration of the two comparor triodes in comparison with the pulse frequency.

The plates 114 and 115 of gas triodes V₁ and V₂, respectively, are connected to terminals 116 and 117 of an anode supply transformer whose primary 118 is connected to the aforesaid quenching supply frequency source 111, secondary connection 117 being a center tap which connects through bridge resistor means 119 to said plate 115 and also to the cathode 120 of triode V₁, said resistor being grounded as at 121, and each bridge resistance section being shunted by capacity 122, while the third terminal of said transformer connects to the cathode 123 of triode V₂.

The outer terminals of the bridge resistor arms connect respectively via conductors 124 and 125 to control grids 126 and 127 of a second pair of gas triodes T₁ and T₂ constituting the master motor control unit, so designated Fig. 2-B, said grids being connected together through the arms of bridge resistor means 129. A biasing voltage supply 130 is connected, positive, to cathodes 131 and 132 of second pair of triodes, and negative to the common connection of the arms of the second bridge resistor means 129 and to ground at 133.

The anode supply voltage for the plates of the second set of gas triodes is procured from the secondary windings 136 and 137 of a transformer whose primary 138 is supplied from the 60 cycle mains, said windings 136 and 137 having a common center tap connection 139 to ground and being respectively connected through motor field windings 136A and 137A to plates 134 and 135; thus, plate current flowing in either triode T₁ or T₂ will excite the corresponding field winding of the Reversible Master Motor 105.

By reason of the normal biasing voltage from source 130, both of the second master control triodes T₁ and T₂ are normally quenched, so that the motor fields are not excited and the motor 105 is at rest; however, an effective positive grid voltage in either arm of the bridge resistor means 119, 129, 121, 133, will fire the corresponding triode, with a resultant excitation of the corresponding field winding 136A or 137A and consequent armature rotation in a certain direction depending upon the poling of the armature supply voltage 140.

An incoming control signal impressed upon the grid of comparor triode V₁ would cause control triode T₁ to fire, and the consequent plate current flow through motor winding 137A would start the master motor in a first direction, with a consequent progressive change in the

capacity of variable control means or condenser 97 of the local generator.

The same incoming control signal would trigger said local generator and the pulse generated thereby would be impressed upon the control grid of the second comparor tube V₂ in phase with the signal voltage applied to tube V₁, so that under the incoming and locally generated pulses, the comparor triodes are fired and restored simultaneously in very rapid succession if the said pulses are identical in length, under which condition, the resultant voltage in the bridge circuit 119, 121, 129, 133, is effectively zero, in consequence of which neither control triode T₁ or T₂ would fire, and motor 105 would be at rest.

However, so long as the incoming and locally generated pulses are of different duration, the aforesaid bridge circuit will be in effect unbalanced with a resultant control voltage that will fire one or the other control triode T₁ or T₂, and the master motor will run until variable control means 97 tunes the local pulse generating means to produce the identical pulse necessary to match the incoming pulse for a zero resultant control voltage in the bridge circuit. In this connection, it is important to notice that the direction of rotation of motor 105 is correlated to the operation of generator capacity 97 and the relative firing relationship of tubes V₁—T₁ and V₂—T₂ such that the relative displacement of capacity 97 will tend to shorten the duration of the local pulse if the latter is too long, and vice versa.

The pulse-duration embodiment of the invention hereinabove described in view of Figs. 2, 2A, 2B, may be utilized to control any desired device or instrumentality, preferably by interconnecting such device with the driving link, indicated by the dash-dot line 142, Fig. 2B, which connects motor 105 with pulse duration control means 97, as depicted schematically by the block controlled device 143 and link line 144, which steps a phonograph selecting switch and circuit of known form, as indicated.

In general, it is important to observe that in this phased-oscillation system there is no reference standard required at the receiving or controlled station, and the transmission can be effected as well by space-wave propagation as by metallic circuit; and while the control system as applied to phonographs, particularly, is commonly coupled to the 60-cycle power mains, any metallic or other transmission circuit will do provided there is a source of relatively low-frequency alternating voltage to power the oscillator; and such voltage may be of a frequency other than 60 cycles.

In the foregoing description it will be noticed that the oscillator of Fig. 2-A operates only on half-cycles of the 60-cycle A. C. supply; however, it will be apparent to those skilled in the art that the oscillator may also be made to oscillate during the full cycle or some portion thereof which is greater than the half-cycle period, regardless of any phased selecting voltage applied to control the pulse emission of the oscillator (i. e. to grid circuit 58).

The maximum period of oscillation of the phased-modulation oscillator of Fig. 2-A is one cycle; but, as a practical matter, where the source of oscillation is a thermionic tube such as the triode 45—46—58, the applied A. C. plate voltage will be effective to produce oscillation only during a portion of the supply voltage cycle, whether this be a half or full-wave operation (as by use of a tube 65 with dual plate and common cathode and control grid in place of the triode of Fig. 2-A).

However, the applied phased-selecting grid voltages are always calculated to modify (and in this sense phasally modulate) the inter-cycle oscillation which actually does occur, so as to determine the effective duration of the oscillatory emission. In this sense, the phased selecting voltages determine in each cycle (or half cycle, or fraction of a cycle) the time length of any pulse or oscillatory emission within a period delimited by the beginning and end of a single cycle of the alternating supply voltage

for the oscillator. In this sense, therefore, the selecting signals may be regarded as phased inter-cycle pulses of selectively variable duration.

I claim:

1. In a remote control system of the type utilizing a 60-cycle A. C. power line, forward pulse generating means including an oscillator having at least a plate circuit and a grid circuit, said plate circuit energized for half-wave operation from said power line, means coupling the output of said oscillator to said power line, means including selecting switches for impressing line-frequency A. C. voltage upon said grid circuit, a phase-shift network electrically associated with said switches and selectively operable to modify the phase angle of the effective voltage impressed upon said grid circuit for the purpose of modifying the time factor characteristic of the output of said oscillator selectively as a phasal function of the power line frequency.

2. In a remote control system of the type utilizing a 60-cycle alternating current power line as a transmission medium, at least; selecting-pulse generating means including an oscillator having at least a plate circuit and a grid circuit, a tank circuit part of said grid and plate circuits, means energizing said plate circuit with alternating voltage from said power line, means coupling the output of said tank circuit to said power line, a phase-shift network selectively variable to impress control voltages from said line upon the grid of said oscillator having different phasal characteristics corresponding to different selecting signals whereby said oscillator emits pulses of different duration depending upon the phasal characteristics selected, and means for timing the duration of emission of any selected pulse signals.

3. A pulse generator for remote control systems comprising a thermionic oscillator having at least a grid circuit and a plate circuit, a resonating tank circuit included as part of said grid and plate circuits, means including a relay connecting said plate circuit to an alternating voltage power line through a momentary starting switch responsive to momentary closing of the latter, timing means in circuit with said relay for disconnecting said plate circuit from said power line following a determined time interval after closure of said switch, a plurality of selecting switches each operable to connect said grid in a different phase-shift circuit with said power line, whereby to cause said oscillator to emit pulses of different duration responsive to closure of said first-mentioned switch, a circuit connection normally preventing oscillation of said oscillator notwithstanding operation of said first-mentioned starting switch, said connection modified by operation of any said selecting switch to permit oscillation following operation of the starting switch, and means coupling the oscillatory output of said oscillator to said power line.

4. Apparatus as defined in claim 3 and further characterized by the provision of a locking circuit controlled by said relay responsive to operation of the latter if said first-mentioned momentary switch is operated, and timing means cooperable with said relay for releasing said locking circuit at the expiration of a predetermined period of time.

5. In a remote control system, a selecting signal transmitter including an oscillator energized from a source of alternating voltage derived from a commercial power line, the output of said oscillator coupled to said line, said oscillator having an input circuit including a phase-shift network and selecting switch means for selectively varying the phasal aspect of a control voltage applied to said input circuit, means coupling said input circuit to said power line for derivation of a control voltage as aforesaid, a coin-controlled switch operable to energize said oscillator, an interlock switch normally rendering said oscillator ineffective to deliver oscillatory energy to said power line, and an operative interconnection between said interlock switch and said selecting switch means which

renders said interlock switch ineffective for normal operation as aforesaid responsive to a selecting operation of said selecting switch means, whereby said oscillator is rendered effective to deliver oscillatory energy to said line in phasally modified signal form depending in phasal aspect upon the selected operation of said selecting switch means.

6. Apparatus as defined in claim 5 and further characterized by the provision of a timing circuit means cooperable with said coin-controlled switch for determining the period of time during which said oscillator will deliver signal energy as set forth.

7. A phased-modulation remote control signal transmitter including an oscillator, a reference source of periodic voltage, a thermionic relay including at least a grid, a plate, and a cathode, selectively variable phase-shifting circuit means connected to phasally modulate said oscillator to impress selecting-signal voltages thereon, a plurality of individual selector buttons each operable to vary the phase-shifting means to select a certain phasally characteristic signal, releasable lock means automatically locking any said button in operated condition, electromagnetic means in the plate circuit of said thermionic relay and operable responsive to predetermined plate current flow in the latter to release said lock means, means coupling the output of said oscillator to a transmission agency for communication of said signals to a remote station, a coin-controlled momentary switch for initially energizing said electromagnetic means, releasable locking means cooperable with said electromagnetic means for holding the latter locked in operated condition upon coin-operation thereof, circuit connections and oscillator control contacts operated by said electromagnetic means in locked operation for rendering said oscillator effective to emit signalling energy and preventing such emission when said electromagnetic means is non-operated, circuit connections and momentary contact means controlled by said electromagnetic means upon said initial operation of the latter to effect momentary release of said releasable lock means for said buttons, time-delay bias means normally biasing said thermionic relay to inoperative condition, and contact means operated by said electromagnetic means in locked operation as aforesaid to start delay operation of said bias means responsive to selecting operation of a said button following coin-switch operation of said electromagnetic means, to nullify said bias and permit current flow in the plate circuit of said relay to again actuate said button lock means and restore said circuit connections and oscillator control contacts to normal condition with said oscillator ineffective to emit signals and said thermionic relay in non-operating condition and to release said locking means cooperable with the electromagnetic means.

8. A transmitter of pulse-duration high-frequency selecting signals comprising a radio frequency oscillator including a modulation circuit controlling an output circuit and powered entirely by an alternating supply voltage of low frequency, said oscillator oscillating at most at most at intervals delimited by the beginning and end of each half-cycle of said low frequency voltage, means for deriving selectively phased selecting signal voltages from said supply voltage at any of a plurality of selectively predetermined phase angles relative to the said half-cycle of supply voltage, and means for applying the phased signal voltages to said modulation circuit of said oscillator to permit the oscillation thereof for intervals the duration of which is a function of the relative phase angle thereof.

9. In a remote control system, a transmitter of pulse-duration selecting signals comprising a high frequency oscillator including a grid circuit and a plate circuit and energized from an alternating voltage source to oscillate at most only during a half-cycle of each period of said voltage, a pulse-duration modulating circuit for impressing signal voltages derived from said alternating voltage

source upon said grid circuit of the oscillator during said period to modify the duration of oscillation during any period aforesaid, selecting means for shifting the phase of said signal voltages relative to said periodic voltage in said modulating circuit to provide a plurality of different selecting-signal oscillator emissions each distinguished in duration from the others, and means coupling the output of said oscillator to a transmission medium.

10. Apparatus as defined in claim 9 and further characterized by the provision of individual manually-operated selecting switches operable to connect phase-shift components with said selecting means and each operable from a normally released condition to operated condition to determine a certain selecting signal voltage phased as aforesaid, mechanical lock means for holding any said selecting switch in operated condition, electrical lock release means, and a coin-controlled initiating circuit for actuating said lock release means to release previously operated switches and to condition said oscillator for effective signal emission for a measured time dependent-
20 ly upon coin operation of said initiating circuit, and manual operation of one of said selecting switches.

11. In a phase-selective signalling system for remote control apparatus, selective signalling means comprising an electron tube oscillator including at least an anode-
25

cathode circuit and a control grid circuit therefore; an alternating-current power source of predetermined frequency connected with said anode-cathode and grid circuits to apply a positive operating potential to said anode-cathode circuit generated during the normal positive half-wave period of each alternation of said source, and further to apply a control voltage from said source to said grid circuit generated during the same half-wave period and in a sense to suppress oscillatory anode-cathode current flow; and selectively-operable phase-shifting means interposed in said circuit connecting said grid control voltage to said grid circuit and operable to shift the phase of the grid control voltage to suppress oscillation for periods of selectively different duration within the limits of a said half-wave period at said predetermined frequency.
